INVENTOR
JOHN KOZIEL
BY *Marvin E. Elkins*
ATTORNEY

UNITED STATES PATENT OFFICE.

JOHN KOZIEL, OF ROTHSCHILD, WISCONSIN.

GRINDING MACHINE.

Application filed May 15, 1922. Serial No. 560,914.

To all whom it may concern:

Be it known that I, JOHN KOZIEL, a citizen of Poland, residing at Rothschild, in the county of Marathon and State of Wisconsin, have invented certain new and useful Improvements in Grinding Machines, of which the following is a specification.

This invention relates to grinding machines, particularly to pedally operated types and has as its object to provide an easily operated grind-stone turning apparatus capable of being actuated by one person having both hands free.

A further purpose is to produce a water containing pan so arranged as to be movable limitedly with respect to the grinding wheel partially immersed therein.

These and other objects, which will become more apparent as the description progresses, are attained by the novel construction and combination of parts hereafter described and shown in the accompanying drawing, forming a material part of this disclosure, and in which:—

Figure 1 is a partial plan view showing an embodiment of the device.

Figure 2 is a perspective view of the same, parts being broken away to show the construction.

The device consists of four posts 10 connected in pairs by side beams 11 and 12, respectively at the top and near the bottoms, and cross beams 13 and 14 at the tops, forming a substantial frame, which also includes a wide beam 15 at the left hand side.

Attached below the beams 12 are brackets 16 in which is revolvably mounted a shaft 17 having a central pedal 20 and an extending end crank 19.

A link 24 is connected with the extending crank 19, its opposite end engaging a crank-pin 25 fixed in the side of a gear wheel 29 meshing with a pinion 28 fixed to the side of the spindle 27 fixed in the beam 15 directly over the shaft 17.

The spur gear 29, meshing with the pinion, is mounted on a spindle 30 and also meshes with a smaller gear 31 fixed on the extending end of a shaft 32.

Said shaft is carried in bearings 33 fixed on the beams 11 and held from longitudinal

movement by the hub of the gear 31 and a collar 34 at its opposite outer end.

Fixed on the middle of the shaft 32 is a grindstone 35 or the like, which upon operating the treadle 20 will obviously be rotated, but at a lower speed than the fly-wheel 26, and hence, due to the reduction of the gearing, quite powerfully.

A pan 36, semi-circular in profile and having its sides spaced to clear the stone 35, has its sides notched to clear the shaft and extends to about the center of the stone, the pan being adapted to contain water in which the wheel rotates.

This pan is supported at its front and rear by flat plates 37 containing elongated slots 38 engaging pins 39 fixed in the beams 13 and 14, the pin in the beam 13 having a thumb nut 40 adapted to clamp the pin in adjustment, the slots permitting the pan to be moved to and from the stone in an obvious manner.

A cover plate 41 is also provided with holes to engage the pins 39, thus forming a level table on which work can be disposed, the stone extending through a central opening in the plate.

A seat 18 for the operator is adjustably secured to one of the posts by a band 21 and support 22, providing a convenient rest during operation.

From the foregoing it will be seen that a convenient and easily operated grinding apparatus has been disclosed which fully meets the objects set forth.

Having thus described my invention, what I claim as new and desire to secure by Letters Patent, is:—

A grinder comprising a rectangular frame, a grindstone rotatable therein, an actuating gear train for said grindstone, pedal means for actuating said train, a pan in which said grindstone operates, said pan having slotted supports resting on the front and rear elements of said frame substantially level with the axis of the stone, to act as a support for work to be ground, and being adjustable to or from the stone, and means for clamping said pan in adjustment.

In witness whereof I affix my signature.
JOHN KOZIEL.
